Primary Examiner — Freda S Nunn(74) *Attorney, Agent, or Firm* — McHale & Slavin, P.A.(57) **CLAIM**

The ornamental design for a cooler liner, as shown and described.

DESCRIPTION

FIG. 1 is a top right isometric view of the cooler liner of the present invention;

FIG. 2 is a top view thereof;

FIG. 3 is a bottom view thereof;

FIG. 4 is a front view thereof;

FIG. 5 is a rear view thereof;

FIG. 6 is a right side view thereof;

FIG. 7 is a left side view thereof; and,

FIG. 8 is an isometric view thereof showing the cooler liner in an environment of use.

Broken lines shown in the drawings represent environment only and form no part of the claimed design.
